CLAIM

The ornamental design for a notebook computer as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion, labeled '9' of FIG. 1;

FIG. 10 is an enlarged view of the portion, labeled '10' of FIG. 2;

FIG. 11 is an enlarged view of the portion, labeled '11' of FIG. 3; and,

FIG. 12 is an enlarged view of the portion, labeled '12' of FIG. 7.

The even dash broken lines illustrate portions of the notebook computer that form no part of the claimed design. The dot-dashed broken lines define the bounds of the claimed design and form no part thereof. The dot-dot-dashed broken lines represent the extent of the detailed views.
